[57] **CLAIM**

The ornamental design for a combination writing instrument and compass, as shown and described.

DESCRIPTION

FIG. 1 is a front elevational view of a combination writing instrument and compass, showing our new design with the writing instrument in operative condition and the compass in closed condition;
FIG. 2 is a side elevational view thereof;
FIG. 3 is a top plan view thereof;
FIG. 4 is a bottom view thereof;
FIG. 5 is a rear elevational view thereof;
FIG. 6 is a side elevational view thereof, showing the side opposite that shown in FIG. 2;
FIG. 7 is a perspective view thereof;
FIG. 8 is a perspective view thereof, shown in open condition for use as a compass;
FIG. 9 is a front elevational view thereof, with the writing instrument in retracted condition;
FIG. 10 is a side elevational view thereof;
FIG. 11 is a top plan view thereof;
FIG. 12 is a bottom view thereof;
FIG. 13 is a rear elevational view thereof;
FIG. 14 is a side elevational view thereof, showing the side opposite that shown in FIG. 10;
FIG. 15 is a perspective view thereof; and,
FIG. 16 is a perspective view thereof, with the compass shown in open condition.
